UNITED STATES PATENT OFFICE.

JAMES M. BUCKLEY, OF KANSAS CITY, MISSOURI.

IMPROVEMENT IN RAILROAD-SWITCHES.

Specification forming part of Letters Patent No. **178,109**, dated May 30, 1876; application filed April 15, 1876.

To all whom it may concern:

Be it known that I, JAMES M. BUCKLEY, of the city of Kansas, in the county of Jackson, and State of Missouri, have invented new and useful Improvements in Railroad-Switches, which improvements are fully set forth in the following specification, reference being had to the accompanying drawings.

Figure 1 is a plan view of my railway-switch, and Fig. 2 is a transverse section of the rail through *w w*; and Fig. 3, a transverse vertical section through *x x*. Fig. 4 is a horizontal section of the rail, and Fig. 5 is a side view of the same.

My invention consists in certain improvements in railway-switches; and has for its object to keep the switch-rails in place, and at all times swung against the head-chairs at the throw of the switch, and thereby prevent the lamination of the ends of the rails by passing trains; and also to provide for the expansion and contraction of the rails, and have the switch-rails move easily at all times in both cold and hot weather.

In the annexed drawings, *A A* represent the head-chairs, in each of which is a transverse slot, *a*, of suitable dimensions. Near the ends of the switch-rails *B B*, at the throw of the switch, is securely bolted a lug, *C*, which extends below the rail and into the slot

of the chair. The slots *a* are curved to the radius of the switch-rails, and the lug *C* moves therein, thereby keeping the ends of said rails snug up against the head-chairs.

At *E* I show a combined carrier and fish-plate bolted to the rails, where the openings are left, to provide for expansion and contraction; and to this end I use a spring, *G*, to keep the switch-rails snug against the head-chairs, the bolt-holes in the carrier *E* being elongated to allow for said expansion and contraction. This can also be used at any point where an open joint is desired. Where wide-headed rails are used a portion of the head must be cut off, to allow the carrier to catch the wheels.

What I claim as new, and desire to secure by Letters Patent, is—

1. The head-chair *A*, provided with the curved slot *a*, and having a lug, *C*, bolted on the switch-rail *B* moving therein, for the purpose herein set forth.
2. The slotted carrier and fish-plate *E*, and spring *G*, in combination with the rails and head-chair, as and for the purpose set forth.

JAMES M. BUCKLEY.
